HAROLD A. WHEELER, OF GREAT NECK, NEW YORK, ASSIGNOR TO HAZELTINE CORPORATION, A CORPORATION OF DELAWARE

ELECTRIC COUPLING CIRCUITS

Application filed September 10, 1930. Serial No. 480,949.

This invention relates to high frequency electric coupling circuits tunable over a range in frequency and adapted more especially for interconnecting successive elements of a high 5 frequency thermionic amplifier or a radio system.

The coupling circuits of the present invention are characterized in that the voltage amplification produced thereby is caused to 10 vary automatically with the frequency of tuning in a manner which is under the control of the designer; the design in general being preferably such as to produce a substantially constant resultant amplification, 15 i. e., uniform sensitivity throughout the tunable frequency range.

With an elementary type of high frequency coupling circuit of which a two-winding transformer having a tunable secondary is a 20 typical example, the variation of amplification with frequency is not under the control of the designer, but increases with frequency throughout the tunable range in a manner well understood, with consequent detrimental 25 effects on the amplification, selectivity and stability of the system.

In the elementary type of coupling circuit referred to above there exists between the primary and tunable secondary circuits a 30 efficient of coupling which is substantially constant throughout the frequency range, a condition which is partially responsible for the mentioned increase in amplification with frequency. The present invention avoids 35 the above noted objections by proper cooperation of different reactance elements in the primary circuit. These provide an effective coupling between input and tunable output circuits which automatically decreases with 40 increase in the tuned frequency, and may be proportioned to offset wholly or in part the factors operative to produce an increase in amplification with frequency.

Coupling circuits broadly operative in accordance with the principles disclosed herein but differing from the present invention as regards both the circuit connections utilized and the specific modes of operation thereof, are set forth in Patent No. 1,763,380 45 issued to C. E. Trube, and in his copending

application Serial No. 101,906 filed April 14, 1926 and Serial No. 120,045 filed July 2, 1926.

The coupling circuits of the present invention embody the following essential elements, namely: a tunable secondary circuit including 55 a fixed inductive winding and a variable capacity bridged between output terminals, and a primary circuit including in closed series connection in the order recited, a fixed capacity, a fixed inductance magnetically uncoupled to the secondary winding, a primary winding magnetically coupled to said secondary winding, an input terminal connected between the fixed capacity and fixed inductance, and a second input terminal connected 60 to an intermediate point of the primary winding. The mentioned connection of the input terminals to the closed primary circuit provides a pair of parallel paths therebetween, one path containing the fixed capacity 65 and a portion of the primary winding, while the other path contains the fixed uncoupled inductance and the remaining portion of the primary winding.

An additional capacity may or may not 70 be connected between the input terminals, or in the operation of the circuit, capacity may exist between these terminals, which is part 75 of the input circuit connected thereto. Irrespective of the particular arrangement utilized, the resultant capacity associated with the inductance of the primary circuit, including the fixed capacity of the closed series connection as well as any capacity existing between the input terminals in the operation of 80 the circuit, should be such as to make the primary circuit resonant at a frequency lower, but not greatly lower, than the lowest frequency of the tunable range.

The objects obtained by such design (1) 85 provide an effective coupling between primary and secondary circuits which automatically falls off as the frequency of tuning is increased but at a rate proportioned to produce a desired variation in amplification with frequency; and (2) control the variations of 90 the input impedance of the coupling circuit throughout the tunable range in such manner as to insure in operation, improved stability, 95 100.

selectivity and sensitivity in the amplifier stages.

The manner in which the results of the present invention are achieved will be more clearly understood upon detailed consideration of the circuit connections set forth in the drawing of which:

Fig. 1 shows in diagrammatic form the elementary coupling circuit of the present invention;

Figure 2 shows the coupling circuit of Fig. 1 as utilized for connecting an antenna circuit to the input of a thermionic valve;

Fig. 3 is a diagrammatic representation of the coupling circuit as employed for interconnecting a pair of screen-grid tubes in cascade relation;

Fig. 4 shows an interstage connection employing triode tubes wherein the coupling circuit is arranged in conjunction with a suitable capacity to provide neutralization of the interelectrode tube capacities, while

Fig. 5 shows a modified form of the invention employed as an interstage coupling circuit.

Corresponding elements are similarly designated in the several figures.

Referring to Fig. 1 of the drawing the coupling circuit comprises a tunable secondary circuit consisting of a fixed inductive winding L and a variable tuning condenser C bridged between output terminals O . The primary circuit associated with input terminals I includes in closed series connection in the order recited, a fixed capacity C_1 , a fixed inductance L_2 magnetically uncoupled to the secondary winding L , and a primary winding comprising the portions L_1 and L_3 magnetically coupled to the secondary winding L . The upper input terminal is connected between the elements C_1 and L_2 , while the lower input terminal is tapped to an intermediate point of the primary winding, as indicated.

The capacity C_2 , shown dotted, is intended to represent the entire capacity effectively bridged between the input terminals I , while the circuit is in operation, and any additional capacities associated with the primary circuit inductance, and in conjunction with capacity C_1 should be such as to render the primary circuit resonant at a frequency slightly below the tunable range of the secondary circuit LC . It is not essential to the operation of the circuit that a capacity C_2 exist between the input terminals I . In the event that the capacity C_2 is zero, however, the capacity C_1 should be of such magnitude as to render the primary circuit resonant at the low frequency above specified.

The elements of the primary circuit as thus proportioned assure that the path between the input terminals I containing the elements C_1 and L_1 will be predominantly capacitive reactive throughout the tunable range and hence of decreasing impedance for

increases in tuned frequency; whereas the path containing elements L_2 and L_3 is inductively reactive and its impedance increases in magnitude with the tuned frequency. It will thus be apparent that the winding portions L_1 and L_3 produce effects in the secondary circuit which vary in opposite fashion with the tuning adjustment. The result is that there is produced an effective coupling between primary and secondary circuits which automatically decreases as the frequency of tuning increases, in a desired manner.

In Fig. 2 the input terminals I of the coupling circuit are connected to an antenna 1 and a ground 2 respectively; while the output terminals O are connected to the grid and cathode respectively of a thermionic tube V_1 . The capacity C_2 of Fig. 1 comprises in Fig. 2 the effective antenna-to-ground capacity of the antenna circuit 1, which in conjunction with the capacity C_1 renders the primary circuit inductance resonant at a frequency below the tunable range.

In Fig. 3 wherein the coupling circuit interconnects a pair of thermionic tubes in cascade relation, the input terminals I are connected to anode and cathode respectively of the first tube V_1 , while the output terminals are connected to grid and cathode respectively of a second tube V_2 . Space current for the tube V_1 is supplied from a battery B inserted in the conductor 3 extending from the point between windings L_1 and L_3 to the grounded conductor 4. The capacity C_2 of Fig. 1 comprises in Fig. 3 the anode-to-ground capacity of tube V_1 which in conjunction with the capacity C_1 renders the primary circuit inductance resonant at the low frequency above specified.

The coupling circuit of Fig. 4 interconnects a pair of triode tubes in cascade relation, each tube having anode, cathode and grid electrodes only. In order to neutralize the grid-to-anode capacity C_g of tube V_2 , a condenser C_n is connected from the anode thereof to the lower terminal of winding L_3 , the latter terminal being of opposite polarity to the upper terminal of winding L , thereby providing a circuit adapted to accomplish this neutralization. The neutralization is accomplished in the manner disclosed in Patent No. 1,489,228 issued to L. A. Hazeltine April 1, 1924. In order to accomplish satisfactory neutralization in this manner, a close degree of magnetic coupling should exist between windings L_3 and L .

The capacity C_2 of Fig. 1 corresponds in Fig. 4 to the total anode-to-ground capacity of tube V_1 which includes the capacity of the neutralizing condenser C_n for this tube, which is effectively bridged across the output of tube V_1 .

Fig. 5 shows a coupling circuit interconnecting a pair of thermionic tubes V_1 and V_2

in cascade relation, which is a slight modification of the circuit of Fig. 1 in that the connection of the input terminals of the coupling circuit are reversed and the location of the B 5 battery in the circuit is changed as required. The circuit of Fig. 5 has certain structural advantages as compared to Fig. 1. For example, with the arrangement of Fig. 5, by winding the coils L_1 and L_3 about the lower 10 portion of the secondary winding L , it is possible to dispense with a physical condenser C_1 since the natural capacity existing between the primary windings L_1 and L_3 and secondary winding L may be utilized for this 15 purpose, leaving the lower terminal of winding L_1 on open circuit.

I claim:

1. An electric coupling circuit tunable throughout a range in frequency comprising 20 a secondary circuit including a secondary winding and variable capacity bridged between output terminals, and a primary circuit including in closed series connection, a second capacity, an inductance winding non-inductively coupled to said secondary, and a primary winding inductively coupled to said secondary, an input terminal connected between said second capacity and inductance winding, and a second input terminal connected to an intermediate point of said primary winding, said primary winding and inductance winding in conjunction with associated capacities having a natural frequency slightly below said tunable range. 35

2. A tuned radio-frequency coupling system comprising a variable tuning condenser, a secondary coil connected in parallel therewith, a primary coil inductively coupled to said secondary coil, an input terminal connected to a tap intermediate the ends of said primary coil, a second input terminal, a fixed capacity effectively connected between said second terminal and one end of said primary coil and a fixed inductance winding non-inductively coupled to said secondary connected between said second terminal and the other end of said primary coil, said primary coil together with said fixed inductance winding and associated capacities having a natural 50 frequency slightly below the tuning range. 100

3. A tuned radio-frequency coupling system comprising a variable tuning condenser, a secondary coil connected in parallel therewith, a primary coil inductively coupled to said secondary coil, an input terminal connected to a tap intermediate the ends of said primary coil, a second input terminal connected to one end of said primary coil through an inductance winding, no connection to the other end of said primary coil, and said primary and secondary coils being arranged to provide natural capacity therebetween, said primary coil together with said inductance and associated capacity having a natural frequency slightly below the tuning range. 115 120 125 130

4. In combination a thermionic tube having anode, cathode and grid, a tuned radio frequency coupling system including a secondary transformer coil and a variable capacity bridged between said cathode and grid, a 70 primary coil inductively related to said secondary, means connecting a first input terminal to an intermediate point of said primary coil and to said cathode, means connecting a second input terminal through a fixed capacity to the end of said primary coil which is of like alternating current polarity to the grid terminal of said secondary coil, a fixed inductance winding connected from the other end of said primary to said second terminal, said fixed inductance winding and primary coil together with the associated capacity in the operation of said system being resonant at a frequency slightly below the tuning range of 85 said variable condenser and a condenser connected from said anode to a point between said fixed inductance winding and primary coil, said condenser being proportioned to neutralize at least in part the interelectrode capacitive coupling of said tube. 90

In testimony whereof I affix my signature.

HAROLD A. WHEELER.
